GAS PUMP AUDITING MACHINE

William D. Pfeifer, East Selah, and
Lloyd Smoot, Yakima, Wash.Application March 30, 1934, Serial No. 718,295
Renewed February 11, 1936

1 Claim. (Cl. 281—8)

This invention relates to an auditing device for gasoline pumps and the like, the general object of the invention being to provide a casing having a window therein, hand operated means for feeding a strip past the window so that it may be written upon to give the names of the customers, the number of gallons sold and the price, with a lamp circuit closed when the pump is operated, and means for breaking the circuit when the hand operated means are operated.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is a front view of a gasoline pump, showing the invention in use thereon.

Figure 2 is a side view, showing the casing in lowered position in full lines and in raised position by dotted lines.

Figure 3 is a top plan view of the device.

Figure 4 is a section on line 4—4 of Figure 3.

Figure 5 is a section on line 5—5 of Figure 4.

Figure 6 is a section on line 6—6 of Figure 3.

Figure 7 is a diagrammatic view of the circuits.

In these drawings, the numeral 1 indicates a casing which has the lower rear corner hinged to a backing member 2, as shown at 3, this member 2 being fastened by bolts 4 or the like to the front of the standard of the pump. A cover 6 is hinged to the upper end of the member 2, as shown at 7, this cover closing the casing when the casing is in upright position, and said cover has a window 8 therein, the upper or inner portion of which is covered by a transparent member 9 and data is placed on the cover, as shown in Figure 3. The cover is formed with a front flange 10 for engaging the upper part of the front of the casing, when the same is in upright position, and a lock 11 is provided for locking the cover and casing together. A roll of paper 12 is supported in the lower part of the casing and the paper passes upwardly over a guide roll 13 in the upper front corner of the casing and then over a shelf forming member 14 in the top of the casing, after which the paper passes over a rear guide roll 15 in the rear corner of the casing, after which the paper passes downwardly

and forwardly and around a receiving roll 16, the ends of which are supported on the track rails 17 connected with the sides of the casing. Spring members 18 tend to hold the roll 16 with the paper thereon against a rubber covered roll 19 having its ends supported in the casing, with one end projecting therefrom into a small casing 20. The rubber coating of this roll 19 is preferably corrugated, as shown. A ratchet wheel 21 is attached to said projecting end of the roll 19 and a handle 22 has one end rotatably connected with a reduced part of said projecting end and carries a spring pressed dog 23 for engaging the ratchet in such a manner that as the handle is pulled forwardly through the slot 24 in the casing 20, the dog will cause the wheel 21 to move and thus impart movement to the roll 19, which in turn causes rotary movement of the roll 16 and the paper thereon so as to feed the paper over the shelf from the main roll 12. A holding dog 25 is provided for the wheel 21 for preventing retrograde movement of the parts and a spring 26, attached to the handle and a part of the casing 20, acts to hold the handle in its rearmost position. Thus by manipulating the handle 22, the paper can be fed across the shelf and under the window 8 step by step, and as a part of the paper is exposed through the uncovered part of the window, this part can be written upon by the attendant so as to record the name of the customer, the name of the attendant, the meter reading, which will indicate the amount of gasoline sold, and also whether the bill is for cash or is to be charged, as clearly shown in Figure 3. On the next movement of the handle to feed another portion of the paper across the shelf, the part last written upon will pass under the glass so that it cannot be changed by the attendant or customer.

A lamp 27 is arranged in a circuit 28 which forms part of a winding for a magnet 29 and this circuit 28 has one terminal connected to a conductor 30 leading from a suitable source of supply and that part of the circuit which forms a portion of the winding of the magnet is connected 40 to a contact 31 for cooperating with a contact 32 on a spring arm 33 which is connected by a conductor 34 to a member 35 forming part of a switch, the other part of which is shown at 36 and is movable toward and away from the part 35 and is connected to the other conductor 30 of the source by the conductor 37. A plunger 38 is arranged in the casing 20 in such a manner that as the handle 22 is moved forwardly, it will strike said plunger and then this plunger 38 will 50

move the switch part 36 away from the switch part 35 and thus break the magnetic circuit which includes the lamp 27. The other part 39 of the magnetic coil 29 is connected by a conductor 40 with the wire 30 and by a conductor 41 to a contact 42 and when the switch 43 for closing the circuit to the motor 44 of the pump is closed, this conductor 41 will be connected to the source through a part of the switch 43 so that the magnet will be energized and this energization of the magnet will attract the member 33 so that the contacts 31 and 32 will engage and thus the lamp circuit will be closed and this circuit will remain closed until it is broken by forward movement of the arm 22 in its feeding action for the paper and when near the end of the forward movement of the arm, it will strike the plunger 38 and thus move the member 36 away from the member 35, which breaks the circuit to the lamp and thus the lamp will be extinguished.

While Figure 1 shows this lamp attached to a part of a pump, it can be placed wherever desired and one of the lamps can be attached to the pump and other lamps can be placed in the office adjacent the pump. Thus the lamp will stay lighted until the arm 22 has been moved forwardly and this lamp or lamps will indicate that the attendant has failed to record the sale.

As will be seen, this invention prevents errors in gasoline sales and protects both the operator and the purchaser and it shows any omission in the recording of sales and whether or not a charge sale has been overlooked and not written up on a sales pad, as frequently occurs. The invention makes it compulsory that each individual sale be registered or recorded whether it is a charge or cash sale, regardless of who made the sale and gives at any time the quantity of gas sold and who

among the staff made the sale. Sales can be checked as to the peak of business and will show the owner when the sales are made and it is practically impossible for a sale not to be recorded as the lamp will continue to burn until the handle has been operated and, of course, before an operator would move the handle he would see whether or not the sale has been recorded. If the machine is re-set and the sale is not recorded, a blank space is shown on the record sheet so that the owner will know that a sale has been made and not recorded. At the end of each day's business, the paper taken from the machine will show the number of cash sales, charge sales and the salesman making the sales. The meter reading on the record sheet will correspond with the meter reading on the pump.

It is thought from the foregoing description that the advantages and novel features of the invention will be readily apparent.

It is to be understood that changes may be made in the construction and in the combination and arrangement of the several parts, provided that such changes fall within the scope of the appended claim.

What is claimed is:—

In combination, an electric switch for closing the motor circuit of a dispensing pump, means for supporting a movable record receiving sheet in record receiving position, manually operable means for moving the sheet into record receiving position, an electric signal, means for energizing the same when the switch is closed to operate the pump, and means for deenergizing the electric signal when said manually operable sheet moving means is actuated.

WILLIAM D. PFEIFER.
LLOYD SMOOT.
